METHOD AND MACHINE FOR SEALING
VITREOUS VESSELS

Daniel S. Gustin, Bloomfield, N. J., assignor to
Westinghouse Electric & Manufacturing Com-
pany, East Pittsburgh, Pa., a corporation of
Pennsylvania

Application May 22, 1937, Serial No. 144,143

13 Claims. (Cl. 176—2)

This invention relates to the sealing of vitreous vessels, and more particularly to tipping off exhaust tubes of incandescent electric lamps containing gas at a pressure higher than atmospheric.

The principal object of my invention, generally considered, is the tipping off of the exhaust tubes of incandescent electric lamps which have been filled with gas at a pressure higher than atmospheric.

Another object of my invention is the provision of a method and machine for tipping off exhaust tubes while enclosed in a space containing gas at a pressure higher than atmospheric.

15 A further object of my invention is the tipping off of exhaust tubes of vitreous vessels, such as incandescent electric lamps, by a sharp oxyhydrogen flame.

Other objects and advantages of the invention 20 relating to the particular arrangement and construction of the various parts will become apparent as the description proceeds.

Referring to the drawings, 25 Figure 1 is a view, partly in side elevation and partly in vertical section, of a fragmentary portion of apparatus embodying my invention.

Figure 2 is a partial elevational, and partial vertical sectional view on the line 2—2 of Fig. 1, in the direction of the arrows.

30 Figure 3 is a fragmentary plan of the apparatus of Figs. 1 and 2, the exhaust tube of the lamp supported thereby being shown in section on the line 3—3 of Fig. 2, looking in the direction of the arrows.

35 Figure 4 is a fragmentary elevational view, with parts in section on the line 4—4 of Fig. 3, in the direction of the arrows.

Figure 5 is a fragmentary horizontal sectional view, on the line 5—5 of Fig. 2, in the direction 40 of the arrows.

Figure 6 is a bottom plan of that portion of the apparatus shown in Fig. 5.

Incandescent electric lamps, as commonly 45 manufactured, include a glass bulb having a reduced or neck portion into which a so-called stem is sealed. The stem includes what is termed a flare tube, one end of which is flanged or flared and sealed to the bulb neck and the other end terminates in a flattened portion or press, through which conductive lead wires are sealed and upon which a filament is mounted. Within the flare tube and extending downwardly from the press are the lead wires, and an exhaust tube leads from an orifice in the flare tube

or press, for the purpose of exhausting the bulb or filling it with gas at a desired pressure.

When manufacturing vacuum lamps, it has been the practice to insert the exhaust tube into a port leading to a vacuum pump and after the 5 air or gas has been exhausted from the bulb, the tube is heated until the wall thereof collapses, whereupon the lamp becomes sealed and may be removed, in a well-known manner, by a pulling or stretching operation.

When, however, the lamp is filled with an inert gas at a pressure higher than atmospheric, the exhaust tube upon being heated will not collapse, but rather tends to expand or blow out due to the internal pressure. The method which I 15 propose to employ for sealing overcomes this tendency to expand or blow out, by performing the tipping off operation in an atmosphere higher than normal atmospheric pressure, or corresponding with the pressure of the gas in the lamp 20 bulb and exhaust tube therefrom, that is, preferably substantially equal to or higher than said gas pressure.

In the drawings of a preferred or selected embodiment of my invention, an incandescent lamp 10 is shown having an exhaust tube 11 inserted in apertured exhaust rubber 12 of a head or exhaust port 13. The head is carried on a conveyor 14 and connected through a vacuum line 15 to suitable vacuum pumps not shown.

Inasmuch as apparatus for exhausting and gas filling lamp bulbs is well known in the art, the mechanism therefor is only fragmentarily illustrated in order to show the improvement embodying the present invention.

The conveyor 14 includes a cap 16 screw-threaded to a fitting 17 and adapted to press a washer 18 through ball bearings 19. The cap may be rotated at the proper time, by means of its laterally extending arm 20, to either press the 40 rubber 12 about the exhaust tube 11 or release the pressure thereon to facilitate insertion therein or withdrawal therefrom of an exhaust tube.

Assuming that the exhaust tube 11 of the lamp 10 has been clamped in the position illustrated and the lamp has been rotated through the stages wherein it was exhausted to the proper degree, the desired inert gas is admitted to the lamp 10 through the exhaust tube 11 from the inert gas line 21, as will be clear from a consideration of 45 Fig. 1. Before admitting gas, however, the vacuum line 16 is cut off from the lamp by pressure applied to the rubber tube connection 22, in a well known manner, as by means of the member 23.

The lamp 10, after being filled with the inert gas to the desired pressure and possibly passing through fires in which the exhaust tube 11 is initially heated immediately beneath the lower 5 part of the stem of the lamp, finally reaches the position illustrated in Figs. 1, 2 and 3, where the tube 11 passes between and separates the baffle plates 24 and 25, as by moving from the left to take the position shown in section in Fig. 3, 10 where it is received in portions of the plates and parts depending therefrom which are notched to provide circular apertures, in which the tube snugly fits when the apparatus is closed.

The baffle plates 24 and 25 carry mechanism, 15 which will now be described in detail, for performing a tipping-off operation on the exhaust tube 11, while the portion of said tube being tipped off is subjected to a pressure higher than atmospheric. Secured to the lower surfaces of 20 said baffle plates 24 and 25 are burner shield sections 26 and 27. These sections have their upper edge portions flanged, as indicated at 28 and 29, and secured to the lower surfaces of the baffle plates 24 and 25, respectively, by any desired 25 means as, for example, welding or brazing 30 and 31.

The baffle plates 24 and 25 are pivotally mounted on a fulcrum screw 32 and together with their supported shields 26 and 27, are normally held 30 in closed position about the associated exhaust tube 11 by means of a spring 33 operating on extensions 34 and 35 from said baffle plates 24 and 25, respectively, so that after the exhaust tube has separated the baffle plates, to the position shown by dotted lines in Fig. 6 while moving in the direction indicated by the arrow, it finally reaches the normal position designated in said figure by the reference character 11, whereupon the baffle plates and associated burner shields 40 close therearound, forming a substantially airtight chamber enclosing the portion of said exhaust tube immediately below the bulb of the lamp 10.

In order to effect a sealing operation in a 45 chamber 59 so formed, the baffle plates 24 and 25 are connected to a gas outlet block designated by the reference character 36. Said block closes the back or right-hand side of the chamber 59 formed by the burner shield portions below the 50 baffle plates as viewed in Fig. 2. Connected to the gas outlet block 36 is a pipe 37 which may supply the desired air pressure to the chamber through port 38.

The front or inner face of the block 36 has 55 an aperture 39 receiving a screw 40 which carries the burner 41. Said burner 41 is generally U-shaped in plan, as shown most clearly in Fig. 5, and provided with ports 42 and 43, for a suitable mixture of hydrogen and oxygen, for example, or 60 a suitable mixture of other combustible gas and oxygen, air, or a mixture thereof. These ports each terminate in a plurality of burner orifices 44 from the port 42, and 45 from the port 43, which orifices are very fine, so that the oxyhydrogen or other flame produced beyond said openings will not backfire and is very fine and sharp.

In order to provide for feeding the gases mentioned to the ports 42 and 43, a gas inlet block 46 is secured to the upper portion of the outlet block 36. The block 46 has downwardly extending ports 47 and 48 with lower openings registering with the upper ends of ports in the outlet block 36 connecting with the burner ports 42 and 43, respectively, so as to provide for the trans-

mission of the gases from the manifold nipples 49 and 50 from the gas mixer.

The rear or right-hand portion of the gas inlet block 46, as viewed in Fig. 5, has arms 51 and 52 straddling the pivot head 53 in order to pivotally support it and associated parts thereon, as by means of pivot screws 54 and 55, which are adapted to be locked in adjusted positions by means of nuts 56 and 57. The baffles, shields and associated parts are normally resiliently held in 10 their uppermost or chamber-closing position by means of a spoon spring 58, the rear portion of which is secured to the pivot head 53 as by means of a nut 72 threaded on the fulcrum screw 32. 15

In order to allow for pivotal motion of the baffles 24 and 25 about their pivot pin or fulcrum screw 32 with respect to the gas outlet block 36 and at the same time allow movement thereof with respect to the connected inlet and outlet 20 blocks, and burner 41, about their horizontal pivot screws 54 and 55, so that the baffles 24 and 25 and the burner shield sections 26 and 27 may be firmly pressed into tight engagement with the adjacent face of the outlet block 36, the front or 25 baffle and shield engaging surface of the gas outlet block 36 is made spherical about a center corresponding with the point of intersection between the vertical axis about which the baffles 24 and 25 pivot, and the horizontal axis about which 30 they are pivoted to the gas inlet, outlet and burner members. This surface is designated by the reference character 63 and the rear upright edges 64 and 65 of the burner shield sections 26 and 27, respectively, are made circular in outline 35 to correspond with the curvature at the places where engagement takes place, as shown most clearly in Figs. 2 and 4.

The rear edges of the lower walls of the burner shield sections 26 and 27 are also formed circular 40 in outline, the narrow outlet-block-engaging faces being correspondingly spherical, as shown most clearly in Fig. 6, and as designated by the reference characters 66 and 67. Likewise, the baffles 24 and 25 have their corresponding edges 45 formed circular in outline, the narrow faces being correspondingly spherical where they engage the gas outlet block 36, as designated by the reference characters 68 and 69 in Fig. 3.

It will therefore be seen that the baffles 24 and 50 25 are free to open and close between the full line positions and those shown dotted in Fig. 6, while at the same time they are free to pivot about their horizontal axis with respect to the gas inlet and outlet burner blocks, to release the gas pressure 55 if it becomes excessive, said baffles and associated parts being normally pressed firmly into engagement with the curved face 63 of the outlet block 36 to form a substantially airtight chamber in which the tipping off operation is performed. 60

In order to limit upward swinging movement of the baffles and associated parts with respect to the inlet, outlet and burner sections 46, 36 and 41, I provide a set screw 70 passing through the gas inlet block 46 and with its lower end normally engaging, or adapted to engage, a flange 71 on the pivot head 53 which rests on the baffles 24 and 25. Said flange 71 has a stud 73 depending therefrom as a locating pin between the baffles 24 and 25. The set screw 70 may be locked in adjusted position by means of a nut 74. 70

It will therefore be seen that the bulb of the lamp 10 may be exhausted, filled with an inert gas and finally moved to a position where that portion of its exhaust tube 11 immediately be- 75

low the neck of the bulb is enclosed in the chamber 59 formed by the baffle plates 24 and 25 above, the burner shields 26 and 27 to the sides and front, and the gas outlet block 36 to the rear. While so enclosed an oxyhydrogen flame, or other hot heating means, is positioned to create a heat zone about the tube 11, at a point designated by the reference character 60, to rapidly seal and cut off the tube while air pressure, supplied from the pipe 37, prevents expansion of the exhaust tube 11, while allowing it to contract naturally, in accordance with the surface tension of the glass, to secure the desired seal. During the sealing or tipping off operation, the lead wires 61 and 62 are of course bent to lie above the baffle plates 24 and 25, protected from damage due to excessive heat.

The baffles are pivotally mounted about a pin so that they may move away from and toward one another to allow for the reception and release of the exhaust tubes of lamps associated therewith, and pivotally mounted about a horizontal axis with respect to the gas outlet block and associated parts while spring-pressed upwardly, thereby maintaining the chamber 59 closed to as great an extent as possible and avoiding an unnecessary escape of compressed air, even when the baffles are open for the reception of an exhaust tube. The bulb of the lamp 10, after being tipped off, may be removed either by hand or by the usual automatic means.

Although a preferred embodiment of my invention has been disclosed, it will be understood that modifications may be made within the spirit and scope of the appended claims.

I claim:

1. The method of sealing a vitreous vessel having an exhaust tube, comprising enclosing only a portion of said tube in a chamber, creating a pressure above atmospheric in said chamber, and tipping off said tube therein.

2. The method of sealing a vitreous vessel having a tubular extension, after said vessel is filled with a gas above atmospheric pressure, comprising enclosing only a portion of said extension in a chamber, creating gas pressure above atmospheric in said chamber, and tipping off the enclosed portion of said extension while subjected to said pressure.

3. The method of tipping off an exhaust tube from a vessel containing a gas at a pressure above atmospheric, comprising enclosing only a portion of said exhaust tube in a chamber, creating a gas pressure in said chamber substantially equal to the pressure in said vessel, and heating said exhaust tube in said chamber until a seal is effected.

4. The method of sealing off a lamp having a bulb with an exhaust tube and containing gas at a pressure above atmospheric, comprising positioning only a portion of the said exhaust tube thereof in an enclosed space, maintaining the gas occupying said space at a predetermined pressure at least as high as that in said tube, and heating said tube to effect a tipping off operation while in said enclosed space.

5. The method of sealing off a lamp having a bulb with an exhaust tube and containing gas at a pressure above atmospheric, comprising positioning only a portion of said tube in an enclosed space, introducing into said space a gas at a predetermined pressure at least as high as that in said tube, and heating said portion to collapse the wall thereof and close the passage in said tube while in said enclosed space.

6. The method of tipping off lamps, comprising enclosing only portions of the exhaust tubes thereof in a closed chamber introducing gas at a pressure above atmospheric, and directing oxyhydrogen flames thereon.

7. A machine for tipping off exhaust tubes of vessels containing gas at a pressure higher than atmospheric, comprising a chamber enclosing a tipping off burner, and formed of movable walls accommodating the exhaust tube.

8. A machine for tipping off exhaust tubes of vessels containing gas at a pressure higher than atmospheric, comprising a chamber defined by pivoted walls enclosing a tipping off burner, accommodating only an exhaust tube, and means for introducing compressed air into said chamber.

9. A machine for tipping off the exhaust tubes of incandescent electric lamps, comprising a chamber defined by pivotally mounted walls which are normally pressed together but movable away from one another to admit exhaust tubes, a tipping off burner normally enclosed by said walls, and means for introducing gas at higher than atmospheric pressure into the space defined by said walls.

10. A machine for tipping off exhaust tubes of incandescent electric lamps, comprising a gas inlet block, a gas outlet block depending therefrom, a pair of baffles pivotally movable about a normally vertical axis, complementary burner shield portions carried by said baffles, said baffles and shield portions being pivotally mounted to rotate with respect to said blocks about a normally horizontal axis, said baffles, shields, and outlet block normally engaging surfaces of one another to define a chamber, a burner block secured to said outlet block and normally enclosed in said chamber, the surface of said outlet block engaged by said baffles and shields being spherical with its center at the point of intersection of said vertical and horizontal axes, the engaged narrow faces at the edges of said baffles and shields being correspondingly spherical, and resilient means for pressing said spherical faces into engagement with said spherical surface to provide a substantially air-tight chamber enclosing said burner.

11. A machine for tipping off exhaust tubes of incandescent electric lamps, comprising a gas inlet block, a gas outlet block depending therefrom, a pair of baffles pivoted about an axis, complementary burner shield portions carried by said baffles, said baffles and shield portions being pivotally mounted to rotate with respect to said blocks about an axis extending at right angles to and intersecting said baffles' axis, said baffles, shield portions, and outlet block normally engaging surfaces of one another to define a chamber, a burner block secured to said outlet block and normally enclosed in said chamber, the surface of said outlet block engaged by said baffles and shields being spherical, with its center disposed approximately at the point of intersection of said axes, the narrow faces at the edges of said baffles and shields which engage said outlet block being correspondingly spherical, and means for pressing said spherical faces into engagement with said spherical surface to provide a pressure-holding chamber enclosing said burner.

12. A machine for tipping off exhaust tubes of incandescent electric lamps, comprising a gas inlet block, a gas outlet block depending therefrom, a pair of baffles, complementary burner

shield portions carried by said baffles, the engaged edges of said baffles and shield portions being notched to provide circular apertures for receiving said exhaust tubes, said baffles and shield portions being pivotally mounted to rotate with respect to said blocks about a normally horizontal axis and normally engaging surfaces of said outlet block to define a chamber, a burner block secured to said outlet block and normally 10 enclosed in said chamber, the surface of said outlet block engaged by said baffles and shields being spherical, with its center disposed approximately at the point of intersection of said axes, the narrow faces at the edges of said baffles 15 and shields which engage said outlet block being correspondingly spherical, and means for press-

ing said spherical faces into engagement with said spherical surface to provide a pressure-holding chamber enclosing said burner and a portion of an exhaust tube.

13. The method of sealing a lamp having an 5 exhaust tube, comprising positioning the end portion of said tube in an apertured exhaust rubber, disposing only an intermediate portion of said tube in an enclosed space, evacuating said lamp, introducing inert gas at a desired pressure above atmospheric through said exhaust tube and into said lamp, admitting gas to said enclosed space to create a pressure therein above atmospheric, and heating said tube in said enclosed space to effect a tipping off operation. 10 15

DANIEL S. GUSTIN.
